US00D822643S

(12) **United States Design Patent** (10) **Patent No.:** **US D822,643 S**
Chen (45) **Date of Patent:** **** Jul. 10, 2018**

(54) **WIRED CONTROLLER**

(71) Applicants: **MPOW TECHNOLOGY CO., LTD.**,
 Hong Kong (HK); **Dongguan Lisong Electronics Co., LTD.**, Dongguan (CN)

(72) Inventor: **Daofeng Chen**, Dongguan (CN)

(73) Assignees: **MPOW TECHNOLOGY CO., LTD.**,
 Hong Kong (HK); **Dongguan Lisong Electronics Co., LTD.**, Dongguan (CN)

(**) Term: **15 Years**

(21) Appl. No.: **29/623,384**

(22) Filed: **Oct. 24, 2017**

(51) LOC (11) Cl. **14-03**

(52) U.S. Cl.

USPC **D14/218**

(58) **Field of Classification Search**

(57) **CLAIM**

The ornamental design for wired controller, as shown and described.

DESCRIPTION

FIG. 1 is perspective view showing my design;

FIG. 2 is another perspective view showing my design;

FIG. 3 is a front view showing my design;

FIG. 4 is a back view showing my design;

FIG. 5 is a left side view showing my design;

FIG. 6 is a right side view showing my design;

FIG. 7 is a top plan view showing my design;

FIG. 8 is a bottom plan view showing my design; and,

FIG. 9 is a use state view showing my design.

The portions of the article shown in broken lines form no part of the claimed design.

1 Claim, 9 Drawing Sheets

FIG. 1

FIG. 2

FIG. 3

FIG. 4

FIG. 5

FIG. 6

FIG. 7

FIG. 8

FIG. 9
